CLAIM

The ornamental design for a tent pole, as shown and described.

DESCRIPTION

FIG. 1 is a front, top perspective view of a tent pole, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the tent pole, shown in a condition of use.

The tent pole is shown with a symbolic break. The appearance of any portion of the tent pole between the break lines forms no part of the claimed design. The broken lines in the FIGS. 2, 4 and 8 illustrate portions of the tent pole that form no part of the claimed design. The broken lines in FIG. 9 illustrate environment and form no part of the claimed design.
